PET ANIMAL MASTICATION AID

Mervin A. Savitt, Kings Point, N.Y., assignor to Reliance International Mfg., Ltd., Hempstead, N.Y., a corporation of New York

Filed Sept. 10, 1962, Ser. No. 71,614

Term of patent 14 years

(Cl. D12—2)

FIG. 1.

FIG. 2.

FIG. 3.

FIG. 4.

FIG. 1 is a top plan view of a pet animal mastication aid, showing my new design;

FIG. 2 is a side elevational view thereof;

FIG. 3 is a right end view thereof; and

FIG. 4 is a view of the opposite end thereof.

The undisclosed side and bottom of the mastication aid are substantially the same in appearance as the side and top view, respectively, shown in the drawing.

I claim:

The ornamental design for a pet animal mastication aid, as shown and described.
